US00D381162S

United States Patent [19]

Berend et al.

[11] Patent Number: Des. 381,162

[45] Date of Patent: Jul. 15, 1997

[54] REFUSE CONTAINER LID

[75] Inventors: Peter M. Berend, Wooster; Stephen P. Casteel, Wadsworth; Charles W. Craft, Apple Creek, all of Ohio; Richard O'Grady, Southington, Conn.

[73] Assignee: Rubbermaid Incorporated, Wooster, Ohio

[] Term: 14 Years

[21] Appl. No.: 53,217

[22] Filed: Apr. 17, 1996

[51] LOC (6) Cl. 09-09

[52] U.S. Cl. D34/11

[58] Field of Search D34/1, 5, 6, 10, D34/11; 220/335, 340, 343, 352, 334, 908, 404; D9/434, 435, 436
